(57) **CLAIM**

The ornamental design for standing tape dispenser, as shown and described.

DESCRIPTION

FIG. 1 is a perspective of the standing tape dispenser in accordance with my design;

FIG. 2 is a left side view thereof;

FIG. 3 is a right side view thereof;

FIG. 4 is a top view thereof;

FIG. 5 is a bottom view thereof;

FIG. 6 is a front view thereof; and,

FIG. 7 is a rear view thereof.

The roll of tape shown in broken lines forms no part of the claimed design.
